FISHING SPINNER

Marion L. Lawhon, Bakersfield, Calif.

Application October 27, 1950, Serial No. 12,755

Term of patent 14 years

(Cl. D31—4)

To all whom it may concern:

Be it known that I, Marion L. Lawhon, a citizen of the United States of America, residing in Bakersfield, Kern County, State of California, have invented a new, original, and ornamental Design for a Fishing Spinner, of which the following is a specification, reference being had to the accompanying drawing, forming a part hereof.

Figure 1 is a perspective view of a fishing spinner embodying my new design;

Figure 2 is a view in side elevation of the fishing spinner; and

Figure 3 is an end view of the same.

I claim:

The ornamental design for a fishing spinner, as shown.

MARION L. LAWHON.
